UNITED STATES PATENT OFFICE.

JAKOB WINDLER, OF THUN, SWITZERLAND.

SAFETY-RAZOR.

1,262,292.

Specification of Letters Patent.

Patented Apr. 9, 1918.

Application filed January 8, 1916. Serial No. 71,099.

To all whom it may concern:

Be it known that I, JAKOB WINDLER, citizen of the Swiss Confederation, residing at Thun, Switzerland, have invented new and 5 useful Improvements in Safety-Razors, of which the following is a specification.

My invention relates to improvements in safety razors of that type which is arranged for use like an ordinary razor and in which 10 a hollow-ground razor blade is used in a holder forming guard and carrier and the handle all made of a single piece of flat metal, and the object is to form of a single piece of flat metal a flat handle portion 15 in alinement and in the same plane with a flat serrated guard integral with a plurality of laterally and oppositely projecting springy clamping ears for gripping around a pair of hollow-ground razor blades.

20 The accompanying drawing illustrates my improved form of construction as hereinafter fully described and stated in the claim.

In the drawing,

Figure 1 is a side elevation of the novel 25 construction, and

Fig. 2 a section on the line *a—a* of Fig. 1.

The safety razor, as is shown in Figs. 1 and 2, comprises the flat guard 1 formed with the usual serrations or teeth 2 and 30 with an integral handle portion 3. Along the upper edge opposite the serrated edge there are formed, by suitably cutting and bending the metal, three springy clamping ears, denoted respectively by 4, 5 and 6, of 35 which those marked 4 are bent laterally to one side and the one marked 5 is bent to the opposite side of the flat guard 1. These ears serve for clamping the thick back of hollow ground razor blades 8. Below the 40 free ends of the ears 4 and 5 respectively there is formed a longitudinal slit 6 with

outwardly turned lips 7 for sustaining the cutting edge of the razor blades at a slight distance from the teeth 2. The provision of clamping ears at both sides of the flat 45 guard 1 enables one razor blade 8 to be secured on the one or the other side of the guard 1 so as to suit the convenience of the user; or two razor blades may be simultaneously held in position as is shown in 50 Fig. 2.

It will be easily understood that an integral handle, flat guard and clamping ears for hollow-ground razor blades can be produced from a single strip of flat metal by 55 suitably stamping and bending same and consequently large numbers of the article can be manufactured very cheaply.

I claim:

A safety razor, comprising a flat guard 60 provided on one edge with serrations and on the opposite edge with three clamping ears formed integral therewith, the two external ears being bent laterally to one side while the middle ear is bent to the opposite 65 side of the guard, the guard being also provided with lips turned out from its body in opposite directions, a blade adapted to be held on the one or the other side of the guard in position by the clamping ears pressing 70 it against the turned out lips keeping it at a distance from the serrations, and a flat handle formed integral with the guard and arranged in a plane therewith.

In testimony whereof I have signed my 75 name to this specification in the presence of two subscribing witnesses.

JAKOB WINDLER.
